PHONOGRAPH

Leland D. Norton and John E. Renholdt, Bridgeport, Conn., assignors to Dictaphone Corporation, New York, N. Y., a corporation of New York

Application April 22, 1936, Serial No. 75,660

2 Claims. (Cl. 274—21)

This invention relates to phonographs and more particularly to phonographs of the record cylinder type for electrically recording and reproducing dictated or other matter. In the present embodiment of the invention an electro-magnetic element suitably related to an acoustically and magnetically responsive diaphragm and serving reversibly either as a sound receiving or transmitting device, may be connected alternatively to an electro-magnetic recorder or to a piezo-electric pick-up or reproducer.

The recording and reproducing devices are both mounted upon a carriage movable for recording in an advancing direction relatively to a record supporting mandrel by the engagement of a feed nut with a rotatable feed screw in a well known manner, and movable in a reverse direction to any desired extent by means of a known form of backspacing mechanism.

Phonographs designed for both recording and reproducing dictation are now generally so constructed and arranged that the carriage for the recording and reproducing mechanism may at any time be manually moved or mechanically backspaced with respect to the record tablet, so as to enable the dictator to reproduce previously recorded matter. When a dictator, using such a phonograph for recording dictation, desires to reproduce previously dictated matter, it is necessary first, to manually readjust the recording and reproducing mechanism to neutral position; second, to move the carriage backwardly along the record tablet a distance depending upon the amount of matter to be reproduced; and third, to set the recording and reproducing mechanism in reproducing position. The apparatus is then in condition for reproducing and the dictator may listen to the recorded matter.

When the reproduction of such matter has been completed and it is desired to dictate further, it is necessary for the dictator to again manipulate the recording and reproducing mechanism to return it to the recording position. Such manipulations incident to a repeating operation in the normal use of dictating machines are distracting, in addition to requiring considerable of the dictator's time. Dictators may often neglect to recondition the recording and reproducing mechanism for recording, after completing reproduction, and in consequence may proceed to dictate while the reproducing stylus remains in engagement with the record tablet with the result that no recording is obtained.

Heretofore various forms of mechanism and controls therefor have been designed with the

object of making some or all of these operations in themselves more or less automatic, some stages in the control of the mechanism from recording to backspacing, then to reproducing, and finally again to recording condition, being designed to follow one another in an automatic manner. In one such arrangement a microphone element served both as a receiver and transmitter, and also a single electrical translation device or sound box served both for recording and reproducing operations. Magnetically operating remote control means were provided for changing the drive of the machine from a condition providing advance movement for recording to one providing a backward movement, during the operation of which control means the recording and reproducing styli were shifted from recording to reproducing position in relation both to the record on the mandrel and to the electro-magnetic sound box. At the end of the backspacing movement it was further possible by the operation of a magnetically operating start and stop control to cause the carriage again to advance, with the reproducing stylus in operative relation to the record.

In order that at the end of reproducing, the sound box might automatically be reconditioned for recording, an advance slide or marker was provided which, normally travelling along with the carriage during its recording movement, was left behind to mark the point of farthest advance of the carriage when the latter was backspaced preliminary to the reproduction of recorded matter. This advance slide, when again picked up by the carriage in its advancing reproducing movement, acted upon certain machine elements automatically to change the sound box and styli from reproducing to recording condition.

In the main, the objects sought for attainment by the present invention are similar, but since in the present instance the recording device and reproducing device are separate and distinct from one another though both borne by the same carriage, it is necessary, when changing from recording to reproducing condition and also when changing from reproducing to recording position, not only to change the relationship of the recorder and reproducer relatively to the record, but also to change the circuit connections of these devices in relation to the single microphone serving as a receiver-transmitter device; and since, in order to have sufficient energy in the voice or speaking circuits to effect satisfactory recording or reproduction, it is advantageous to include an amplifier in such circuits, the change from one condition to another includes reversing the connections to and

from the amplifier so that in one instance the microphone element is connected through the amplifier to the recorder, and in the other the reproducer is connected through the amplifier to the said microphone element.

One of the objects of the present invention is to provide in apparatus of the above character means operable after the termination of a period of recording, efficiently and simply, and by the use of a single remote control, successively and automatically to condition the recorder and reproducer mechanisms and their electric circuit connections for reproducing operation, effect a backspacing movement of the carriage, then effect an advance movement of the carriage during which movement the record is reproduced, and when the carriage reaches the point where the backspace movement began, immediately recondition the recorder and reproducer mechanisms and their electric circuit connections for subsequent recording.

The invention accordingly consists in the features of construction, combinations of elements and arrangements of parts as will be exemplified in the structure to be hereinafter described and the scope of the application of which will be indicated in the following claims.

In the accompanying drawings in which is shown one of the various possible embodiments of the invention,

Fig. 1 is a front elevation of an electric dictating machine embodying the invention, the front of the sub-base or motor box being removed to show the driving motor and, in vertical section, the clutch mechanism associated therewith. This view also shows a magnetically operated circuit changer in front elevation.

Fig. 2 is an end elevation of the machine as viewed from the left of Fig. 1, the end of the motor box being cut away. The section through the motor shaft and clutch is taken on line 2-2 of Fig. 1.

Fig. 3 is a cross-section taken on line 3-3 of Fig. 1 showing the carriage for the recorder and reproducer and also a farthest advance marker, in right elevation.

Fig. 4 is a section taken on line 4-4 of Fig. 3.

Fig. 5 is a section taken substantially on line 5-5 of Fig. 4.

Fig. 6 is a cross-section through the backspacing mechanism substantially on line 6-6 of Fig. 1 showing the carriage in left side elevation.

Fig. 7 is an enlarged fragmentary cross-section taken on line 7-7 of Fig. 4.

Fig. 8 is a plan view of a switch carried by the advance marker as viewed from the position of line 8-8 of Fig. 3.

Fig. 9 is a cross-section taken substantially on line 9-9 of Fig. 2 showing in enlarged detail a portion of the backspace actuating mechanism.

Fig. 10 is a detail view of certain parts of the backspace actuating mechanism omitting parts lying in front of line 10-10 of Fig. 9.

Figs. 11 and 12 are enlarged perspective views of cooperating parts of the backspace actuating mechanism.

Fig. 13 is an elevation of the magnetically operated circuit changing switch, taken on line 13-13 of Fig. 1.

Fig. 14 is a fragmentary section taken on line 14-14 of Fig. 13.

Figs. 15, 16 and 17 are wiring diagrams showing the various electric circuits of the machine, with control devices conditioned for backspacing, recording and reproducing.

Fig. 18 is in part an elevation and in part a longitudinal section of a hand unit including a microphone and remote control switches; and

Fig. 19 is a fragmentary perspective view of a portion of the carriage, the advance marker and the carriage guide rod.

Referring to the drawings, and more particularly to Figs. 1 and 2, the phonograph will be seen to comprise a frame the base 50 of which is hinged as a cover for a motor box or sub-base 51. The frame also comprises an integral housing 52, serving as a bearing for a mandrel shaft 53, and left- and right-hand standards 54 and 55.

Mandrel drive

The mandrel shaft is provided with a record support or mandrel 56 at one end and a fixed pulley 57 at its other end. Power for driving the pulley 57 is derived from an electric motor 58 located in the sub-base or motor box and resiliently suspended from the base 50 in any suitable manner. Engaging the pulley 57 is a belt 59 which extends through an opening in the base plate 50 to a pulley 60 mounted on the left-hand end of a short countershaft 61. The right-hand end of the shaft 61 is connected through a clutch mechanism 62 to the shaft 63 of the driving motor. The clutch 62 comprises a sleeve 64 fixed to the inner end of the shaft 61 by means of a set screw 65. This sleeve is also rotatably supported on the outer end of the motor shaft 63, the said sleeve surrounding the adjacent ends of the two aligned shafts.

As shown in Fig. 1, in the lower part of the sleeve a pin 66 is mounted transversely with respect to the axis of the two shafts, and a latch 67 provided with a projecting abutment 68 is pivotally mounted on said pin. Bearing downwardly against the left-hand end of the latch 67 is a pressure spring 69 held in place by means of the set screw 65. This spring tends normally to turn the latch 67 in a counter-clockwise direction about the pin 66. When the latch is rotated sufficiently under the pressure of the spring 69, the right-hand end of the latch engages a depending lug 70 on a drive dog 71, which is fixed upon the motor shaft. When the latch and lug are in engagement the shaft 61 is connected to the motor shaft so that operation of the motor will rotate the pulley 60, and through the belt 59 and pulley 57 drive the mandrel and mandrel shaft.

Since the latch is normally biased by its spring into clutching relation with driving dog 71, means is provided normally to hold the latching member out of clutching relation with the said dog against the reaction of the spring 69. This means comprises a camming lever 72 best seen in Fig. 2 which in its normal position, as shown in Figs. 1 and 2, holds the clutch elements in an unclutched condition. The camming lever 72 is connected by pin and slot arrangement with the armature 73 of an electro-magnet 74 which magnet has an energizing coil 75. When the magnet is energized the armature 73 is drawn up throwing the camming lever 72 out of contact with the latch lug 68 so that the latch under the influence of its spring makes engagement with lug 70 connecting the motor with the shaft 61.

The disconnecting action is made possible by the formation of the free end of the lever 72 which is tapered to form a cam against which the downwardly projecting abutment 68 on the latch member, rotating with its associated parts,

will impinge when the lever 72 returns to the position it will occupy when the magnet is de-energized. When the abutment 68 engages the camming lever 72, the further rotation of the two shafts and of the sleeve 62 causes the latch to be turned about its pivot pin gradually until the latch disengages the lug 70 thereby disconnecting the shafts. No claim is made in the present application to this clutch per se, and for a more detailed description thereof reference may be had to United States Patent 1,892,669.

Rotatably mounted in the standards 54—55 is a feed screw 76 (Figs. 1, 3 and 6) which is driven at a definite speed ratio with relation to the mandrel shaft by a train of gears, not shown, connecting said feed screw with the mandrel shaft.

The carriage

A carriage 77 upon which is mounted an electro-magnetic recorder 78 and a piezo-electric reproducer 79 is supported for longitudinal movement relatively to the record support 56 upon a front main carriage rod 80, pivotally mounted between standards 54 and 55 and adapted to serve as a rock shaft for operating backspacing mechanism, indicated generally by the reference numeral 81, forming part of the carriage equipment.

The carriage has a rearwardly extending portion 82 (see Fig. 6) which at its end has sliding engagement with a rear carriage rod 83 rigidly supported at one end by the housing 52 and at the other by the standard 55.

The carriage is further provided with a control lever 84 pivotally mounted upon a carriage sleeve 85 which surrounds the carriage rod or rock shaft 80 and is slidable thereon. This control lever, as will be more fully described hereinafter, serves the double purpose of alternatively conditioning the recording and reproducing devices in an operative or in a non-operative relationship to the record support, and of simultaneously engaging or disengaging a feed nut 86 with the feed screw 76. When this lever is in its raised position, the carriage may be freely moved to and fro upon the guide rods by hand. When the carriage feed nut is in engagement with the feed screw, the carriage may be moved from left to right for the purpose of recording dictation upon a record cylinder carried upon the mandrel or, when properly conditioned, to reproduce as sound waves matter previously recorded.

Referring to Fig. 6, it will be seen that the feed nut 86 is carried upon one end of a lever 87 pivoted at 88 and having at its upper end a portion 89 disposed in operative relation to a cam 90 formed upon the lever 84. Thus when the lever 84 is lifted, the lever 87 is moved about its axis to remove the feed nut 86 from the feed screw 76.

Backspacing mechanism on the carriage

The carriage may also be backspaced automatically by remote control through mechanism, hereinafter described, for oscillating the rock shaft 80, which rock shaft is connected in a known manner by means of a movable spline 91 with the carriage sleeve in such a way as upon repeated oscillation of the rock shaft to effect a continuous step-by-step backspacing movement of the carriage. Connected also with this backspacing mechanism is means adapted to lift the feed nut from the feed screw each time the rock shaft moves in a direc-

tion to backspace the carriage, the release taking place prior to the action of the backspacing mechanism. Forming part of the carriage backspacing mechanism is a cam sleeve 92 which effects operation of the feed nut to disengaged position, and simultaneously by reason of a cam projection 93 engaging the end of a lever 94 rocks the said lever about its pivot 95 to throw the upper end 96 toward the front of the machine to hold the reproducing stylus in a centralized position as will be hereinafter described. For a more detailed description of the backspacing mechanism comprising the movable spline, its camming connection with the carriage and the feed nut actuating connections, reference may be made to U. S. Patent No. 2,070,180.

Backspacing mechanism on the frame

At its right end the rockshaft 80 is rotatably mounted in the standard 55 as by the bushing 97. Referring to Figs. 1, 2, 9, 10, 11 and 12, at the other end the rockshaft is provided with a shoulder portion 98 beyond which extends a bearing portion 99 adapted to interfit with a socket 100 formed within a bushing 101 and to be held against rotative movement relatively to said bushing by the engagement of the shoulder portion 98 with a slotted portion 102 of the bushing. The left-hand bracket 54 of the frame is bored at 103 and counterbored as at 104 to provide a shoulder at 105. This shoulder forms a stop for the inner end of a sleeve 106 press fitted within the counterbore 104, and adapted rotatably to support the bushing 101. The latter is provided with a flange 107 for engagement with the said inner end of sleeve 106.

Beyond the outer end of sleeve 106 which is flush with the outer wall of the bracket, the bushing 101 extends a short distance at a slightly reduced diameter providing a seat 108 for a loosely mounted washer or collar 109. Beyond the seat 108 the bushing extends at a still smaller diameter to provide a projection 110, squared on two sides as at 111. Upon this projection is mounted non-rotatively a crank arm 112. The outer end of bushing 101 is drilled and tapped to receive a shoulder screw 113 carrying rotatably mounted thereon a control lever 114 which is adjustably secured to the crank 112 at the upper ends of the two members by means of a cap screw 115 threaded into the crank arm and passing through a slot 116 in the control lever. Between the control lever and the shoulder of screw 113 is provided a flanged sleeve 117.

Preferably the power for rocking the rockshaft 80 is taken from the pulley 57. For this purpose, the hub of the pulley is provided with cams 118 adapted to engage an interponent 119 pivotally mounted on the sleeve 117 loosely enough to rock or cant sideways thereon. The interponent is coupled with the control lever 114 by a tongue 120 which fits loosely within a slot 121 in the control lever. When the end 122 of the interponent lies in the path of the cams 118, the interponent will be, by engagement with said cams, intermittently rocked, rocking with it the control lever which in turn operates the rockshaft 80 through the crank arm 112. This operation will continue indefinitely so long as the end 122 of the interponent is allowed to remain in the path of the cams.

However, the end of the interponent is not always in the path of the cams, but is normally during the operation of the machine, except when backspacing, held out of said path by a trip lever

123 having a cam surface 124 arranged to be engaged by a lug 125 on the interponent 119. The trip lever is pivotally mounted on a stud 126 and when released from engagement with the lug 125 by means hereinafter described, permits the interponent to cant sideways to swing its end 122 into the path of the cams 118 by a spring 127 carried by a stud 127'. This canting movement is permitted by the loose mounting of the interponent on the sleeve 117, and the interponent is kept in coupled arrangement with the control lever 114 during this movement by the pin-and-slot connection 120, 121. The stud 127' is threaded into the control lever 114 and passes loosely through an opening in the interponent.

After each operation of the interponent 119 by actuation of the trip lever 114, it is automatically rendered inoperative by being moved out of range of the cams 118 by the re-engagement of the lug 125 with the trip lever as the latter returns to its normal position after being actuated and released, and is then in position to engage the lug 125 with its cam surface 124 to swing the interponent out of the path of cams 118.

It will be understood that if the trip lever is held in its actuated position, the interponent will continue to lie in the path of the cams 118, and the step-by-step backspacing movement will continue until the carriage reaches the limit of its backward travel. After each forward rocking movement of the rockshaft, control lever and interponent, these parts are returned to their normal position of rest by the spring 128 which connects a rearwardly extending lower arm 129 of the control lever with the frame of the machine. The said position of rest is determined by the engagement of a cushioned abutment 130 on the control lever with an adjustable stop 131 on the frame. For a more complete showing of the rockshaft rocking mechanism above described, reference may be had to U. S. Patents 1,649,965 and 1,983,039.

Remote control is provided for effecting actuation of the trip lever 123. This comprises a solenoid 132, the core 133 of which is connected to the lower end of the strip lever by a pin-and-slot connection 134. This solenoid is suitably mounted on the base plate 50 and is energized for backspacing the carriage by electrical connection with the power circuit of motor 58 through the manual closing of a switch 135 by means of a push button 136 mounted upon the microphone supporting hand unit 137, as will be more fully described in connection with the wiring diagrams, Figs. 15, 16 and 17.

When the solenoid core is attracted by energization of the solenoid coil the trip lever is moved to release the lug on the interponent 119, thus conditioning the machine for intermittent and continuous backspacing as above described. Upon de-energizing the solenoid by release of the push button, the trip lever is returned to its unactuated position by means of a spring 138 extending between the said lever and the front of the frame, and as explained above the interponent is forced out of the path of the cams 118, and the backspacing operation terminated.

Recording and reproducing devices and their condition controlling mechanisms

Referring to Figs. 1 to 7 of the drawings, the front portion of the carriage will be seen to be curved concentrically with respect to the man-

drel. The upper part of this curved front divides to form a half yoke as at 140 in Fig. 1. At the upper end of this yoke a plate 141, formed integrally with the yoke or secured thereto in any desired manner, extends rearwardly above the mandrel inclining upwardly at a slight angle from the horizontal, and depending therefrom at its rear end is a downwardly extending plate 142 disposed substantially at right angles therewith and located behind the mandrel. These two right angularly joined plates support the recording and reproducing devices, together with means for effecting the conditioning of said devices for recording and reproducing, for free shifting of the carriage by hand and for remote control backspacing.

The recorder 78, best seen in Figs. 3, 4 and 6, comprises a recording stylus 143 supported at one end of a stylus carrier 144 pivoted at 145 between a pair of downwardly extending bracket members forming part of a weight lever 146 which at its forward end is pivoted, as at 147, for rotational movement about a horizontal axis, between the downwardly extending sides 148 of a bracket secured to or forming part of a circular base 149, which base is formed and adapted to fit within a circular socket 150 located in the plate 141 forwardly of the mandrel axis. A rod 151 operatively connects the stylus carrier with a vibratory member of any suitable translation device capable of causing vibration of the stylus carrier in accordance with the frequency and magnitude characteristics of voice currents acting upon the said device. Preferably an electromagnetic motor, not shown, mounted within the cover 78' is employed for this purpose.

The weight and manner of control of the weight lever 146 is such that the stylus is normally held in operative engagement with the record cylinder. At the rear of the weight lever 146 there extends still farther to the rear of the machine a tongue 152 which may be best seen in Figs. 3, 4, 6 and 7. When the weight lever is not lifted by the engagement of the stylus with a record, the tongue 152 will normally rest upon the forwardly extending arm 153 of a lever 154 pivoted at 155 in the rear carriage plate 142. This lever is pivotally connected as at 156 to a link 157, the other end of which is pivotally connected to the core 158 of a solenoid 159 whose purpose will be more fully described hereinafter. In the normal unexcited condition of the solenoid, the arm 153 of said lever 154 is held in the position shown by means of a compression spring 159'.

Mounted to swing about a pivot 160 in the back plate 142 in a path substantially parallel to said back plate, is a bracket member 161 having an upwardly extending arm 162 and a forwardly extending arm 163. Pivotally supported as at 164 upon said bracket is a dog-leg shaped lever 165 which is slotted for a distance between its ends so as loosely to embrace the bracket 161 and is movable about its pivot 164 toward and away from the record and, by reason of the pivotal mounting of the bracket 161, is adapted to have limited movement laterally in respect to the sound track upon a mandrel supported record cylinder.

At its lower end the lever 165 supports in any suitable manner a piezo-electric reproducing unit or pick-up which comprises, in its construction, a reproducing jewel or stylus 166 supported by means of a resilient member 167 exteriorly of an insulative and protective case 168 within which

is operatively mounted a piezo-electric crystal unit 169 including electrodes, not shown, which may be connected by means of flexible leads 170 and 171 to the input circuit of any suitable voltage amplifier.

In the present embodiment of the invention such an amplifier, indicated by the numeral 40 in the wiring diagrams, may have its output circuit connected to the microphone unit 41 mounted within the hand unit 137, Fig. 18 of the drawings. This microphone may also be connected by a circuit changing device 42, to be hereinafter described, to the input circuit of the amplifier 40 which would then by the same circuit changing means have its output circuit connected to the magnetic recorder 78.

The reproducer stylus or jewel supporting member 167 is connected by means of a suitable bridge member 172 (see Figs. 3 and 5) with the crystal unit 169 in such a way as to cause variable flexure of the crystal unit in accordance with the wave form of the record sound track when the stylus is disposed in operative relation thereto and thus produce, in a well known manner, variable voltages in the input circuit of the amplifier corresponding with the pressures due to such flexure.

A spring 173, best shown in Fig. 7, connects the lower part of lever 165 with the forward arm 163 of bracket 161 in such a way as to pull the reproducer unit toward the record. However, under ordinary conditions the reproducer stylus will not be able to engage the record since the forward movement of the lower end of the reproducer supporting lever 165 is limited by the engagement of the upper end 174 of such lever with an abutment 175 on the lever 154. The normal position of lever 154 is such that the recording stylus 143 may engage the surface of a record of maximum or minimum thickness. When, however, the solenoid core 158 and lever 154 are drawn up by energization of the solenoid 159 against the reaction of spring 159', the recorder is lifted off the record by arm 153 of lever 154 and, since during this movement of the lever the abutment 175 lifts away from the forward end 174 of lever 165, said lever 165 may move forwardly about its pivot 164 until the reproducing stylus comes into operative contact with the record cylinder. When the solenoid is de-energized the lever 154 will again be moved to its normal position by the spring 159' forcing the reproducing stylus away from the record and permitting the recording stylus to descend thereupon. The electric circuits and control means by which the solenoid 159 is controlled in its operation will be fully described in connection with the wiring diagrams.

Manual means is provided for changing the condition of the recorder and reproducer from the normal situation wherein the recorder is in operative relation to the record, to a condition wherein both recorder and reproducer are inoperatively stationed with respect to the record. This is accomplished by means of the conditioning lever 84, hereinbefore mentioned. The lever 84 is provided with a forwardly projecting lug 176 (see Figs. 1 and 6) which, when said lever 84 is manually raised, engages and swings upwardly an arm 177 pivotally mounted on the carriage by a screw 178. Arm 177 is pivotally connected as at 179 with a push rod 180 which, passing through an opening 181 in the carriage yoke, extends upwardly and rearwardly to a point beneath the rear portion of the carriage plate 141 where it is

pivotaly connected, as at 182, see Figs. 3 and 4, to a crank arm 183. The latter is adjustably clamped by means of a screw 184 upon a shaft 185 supported in bearings 186 depending from the under side of the carriage plate 141. At its opposite end this shaft carries a bent rod 187 which is formed to underlie the tongue 152 of the recorder weight lever 146. Another bent rod 187' carried by shaft 185 is provided with a plate 188 adapted to engage an upwardly facing plane surface 189 of lever arm 174.

When the carriage lever 84 is in its lower position the members 187 and 188 will stand as in Fig. 7 and have no effect upon the position of the recorder and reproducer elements; but when the lever 84 is lifted to rock the shaft 185 in a clockwise direction as seen in Figs. 3 and 7, the rod 187 will engage the tongue 152 and lift the weight lever 146 so as to render the recorder inoperative in respect to the record. At the same time the plate 188 will descend upon the plane surface 189 of lever 165 moving the end 174 of said lever slightly away from the abutment 175, thus withdrawing the reproducer further away from the record cylinder and at the same time, by reason of the engagement of the two plane surfaces 188 and 189, effecting a centralizing of the reproducer element in respect to a vertical plane passing through the axis 160.

Lateral movement of the reproducer unit about the axis 160 is provided to permit lateral freedom of movement of the reproducing stylus so that it may follow the sound track on the record freely and without danger of skipping from one track to another. Also, since the reproducer stylus is a tracer element, it must have this freedom to prevent the side walls of the record groove from binding the reproducer stylus and preventing its accurately following the hill-and-dale sound track. During operation the reproducing stylus is apt to lag behind the travel advance of the carriage; thus, by providing means for bringing the reproducer to a centralized position while it is off the record, assurance may be had that when brought into engagement with the record the reproducer stylus will be properly positioned.

Mechanism has been described hereinbefore for backspacing the carriage step by step toward the beginning of the sound track on the record cylinder, that is, toward the left end of the cylinder as seen from the front of the machine. Since this backspacing in the present machine is remotely controlled, it is necessary that the recorder be automatically brought to its inoperative position before actual backspacing begins. It will be understood that if the dictator has recorded certain matter on the record cylinder and wishes to go back to some point in such recorded matter to have it repeated, he may accomplish this either by raising the carriage lever 84 and sliding the carriage by hand to the desired point, or, with the carriage lever 84 untouched, may by operating the remote backspace control energize the solenoid 159 and so recondition the parts that the recorder is held off the record and the reproducer is permitted to engage the record, as hereinbefore described. During automatic backspacing the reproducer will be backspaced with the carriage with its stylus in engagement with the record cylinder.

Since this backward movement of the carriage and the drag of the cylinder tends to turn the reproducer unit about its axis 160 out of its centralized position so that, when at the end of

backspacing, the machine is conditioned for reproducing, the reproducing stylus may improperly engage the sound track on the record, means is provided for positively centralizing the reproducing mechanism each time the backspacing mechanism makes one of its intermittent step by step movements. This means comprises a lever 190 (best seen in Figs. 4 and 5) pivoted in a lug on the under side of the carriage plate 141, as at 191, and extending beyond the transverse centerline of the carriage. Centrally disposed with respect to said transverse centerline, a V-notch 192 is formed in the lever 190 the walls of which notch are adapted to be brought into engagement with the upper end of arm 162 of bracket 161 to positively centralize the bracket 161 and the reproducer unit carried thereby.

Lever 190 is moved into engagement with arm 162 by means of a link 194 which is pivotally connected at 195 with the lever 190 and at its forward end is provided with a slot 193 through which the upper end 96 of the hereinbefore-mentioned lever 94 extends. A spring 196 connects the said lever end 96 to a lug 197 on link 194 so as normally to hold link 194 in a forward position with lever end 96 located at the rear end of slot 193 and the notch 192 out of registry with arm 162. During backspacing, each time the rock shaft 80 oscillates to backspace the carriage, the lever end 96 is swung toward the front of the carriage. This movement is transmitted to the link 194 through the spring 196, resiliently effecting a forward movement of lever 190 into centering engagement with the bracket 161.

Since it is desirable, when the parts are automatically changed from recording to reproducing condition by the energization of the solenoid, to prevent such rapid action of the solenoid connected parts as to cause the reproducing stylus too actively to engage the record cylinder and perhaps damage the delicate piezo-crystal unit, the forward end of lever 154 is connected by means of a rod 198 to the plunger 199 of a dash-pot 200. The action of this dash-pot slows up the response of the parts to solenoid energization and likewise, when the magnet is de-energized, retards the movements of the same parts in response to the reaction of spring 159, thus preventing the recording stylus from returning to its normal position in contact with the record cylinder with too great force.

It will be apparent through reference to Figs. 3, 5, 6 and 7, that the solenoid 159 is mounted upon the carriage plate 141 rearwardly of the recorder, and it will be understood that all parts not intended to be influenced by magnetic action are preferably made of non-magnetic material such as brass or suitable aluminum alloys.

Advance marker slide

Mounted on the carriage and extending outwardly from the side of the carriage in the direction of the forward advance thereof (the right side in Fig. 1) is a pin 201 (see Figs. 1, 3 and 8) adapted during the normal operation of the machine for recording to separate the contacts 202 and 203 of a switch 204 mounted upon a farthest advance marker plate 205. This plate, shaped somewhat like the lower portion 82 of the carriage, is slidably mounted to the right of the carriage upon the carriage rods 80 and 83. Switch 204 comprises a short spring contact member 206 and a long spring contact member 207 insulated from each other and from the marker plate by suitable insulation plates 208, 75

and fastened to the advance or right side of the marker plate by means of screws 209.

When the marker plate and carriage are brought together side by side, pin 201, passing through a hole 210 in the marker plate, engages the longer spring member 207 and forces it away from spring member 206 a sufficient distance to break contact between the switch members. When the carriage and marker are separated slightly as by a single backspacing movement of the carriage, the consequent withdrawal of pin 201 permits engagement of the switch contacts thus closing an electric circuit therethrough, as will be hereinafter described. It should be understood at this point that the translation devices on the carriage cannot be conditioned electrically for recording unless the carriage and marker are together and the circuit between the switch contacts broken.

When during operation of the machine, after first lifting the carriage lever 84, the carriage is moved to its initial position adjacent the left end of the mandrel, as when it is desired to change records, it is desirable, in order that the recorder may be in operative condition, simultaneously to return the advance marker along therewith. Co-operating means, best seen in Fig. 19, located respectively on the carriage and the marker accomplish this purpose. The means on the carriage comprises a marker return lever 211, rotatively mounted on the carriage sleeve 85 at the right side of the carriage. The carriage sleeve is reduced in diameter beyond the side of lever 211 as at 85' to provide a threaded portion adapted to receive a nut 212 which, when turned down to the shoulder provided by said reduction in the sleeve diameter, will hold the lever 211 in pivoted relation to the said sleeve.

The forward end of the marker plate 205 is provided with a sleeve 205' slidably mounted on the carriage rod 80, said sleeve being provided with a collar 205'' of larger diameter on the side adjacent the carriage. This collar is cut away to provide a relatively wide sector-shaped notch 213 and a relatively narrow sector-shaped notch 214, the latter located in that part of the collar which lies nearest the carriage. Thus is formed an abutment 215. Rigidly mounted in and passing through a portion of lever 211 in horizontal alignment with the notch 214 is a rod 216 one end of which is bent down to form a hook 217 which normally lies beyond notch 214 within notch 213 when the carriage and marker are side by side, and which is adapted, when the lever 211 is raised, to pass behind the abutment 215 and thus lock the carriage and marker together, whereby the marker is compelled to return with the carriage when the latter is moved to its initial position.

A shoulder 218 formed on carriage lever 84 provides a notch 219 between said shoulder and the lug 176, hereinbefore mentioned. The location of this notch is such that when both levers 84 and 211 are in their lower positions as during recording, the extended rod 216 passes therethrough at a point just forwardly of said lug 176. In this position of the parts the lever 84 may be raised to release the feed nut from the feed screw and to condition the translation devices inoperatively in respect to the record without shifting the lever 211, so that the carriage may be moved to the left by hand without changing the advance marker from its position of farthest advance.

On the other hand, when the lever 211 is

raised to lock carriage and marker together, the lever 84 is also raised by contact of the rod 216 with the lug 176, thus conditioning the carriage elements for free movement of carriage and marker along the carriage rods. Upon release of lever 211 it will fall back of its own weight against the shoulder 218 of lever 84, the latter remaining in its raised position, because of the reaction of the feed nut lever 89 and lever 94 upon the respective cams 90 and 93, until again lowered by hand by the dictator. To prevent too free movement of the advance marker it is provided with a frictioning device comprising a set screw 220 which seats with adjustable pressure against a friction washer 221 disposed in a 15 threaded opening 222 formed in the collar 205", the said washer being in contact with the carriage rod 80.

Microphone hand unit

The microphone hand unit 137 (see Fig. 18) includes a mouthpiece 137' secured in any desired manner to a handle 137". The electro-magnetic microphone 41, serving both as receiver and transmitter for the phonograph, is mounted in operative relation to the mouthpiece within the upper part of the handle. Any microphone of this type having proper characteristics may be employed and may include in its construction a vibratory magnetically attractable diaphragm 41^a, suitably mounted in operative relation to the poles 41^b of any suitable electro-magnetic microphone unit 41^c mounted within an insulative casing 41^d.

The backspace control switch 135, mounted within the handle 137" has already been mentioned. It is a three-pole switch comprising spring contact members 135^a, 135^b and 135^c suitably supported in the insulation block 135^d. Normally these contacts are biased out of engagement but may be brought together by pressing the push button 136. As will be described hereinafter, this switch also constitutes one of the controls for effecting operation of the circuit changer 42.

Suitably mounted within the handle 137" below the switch 135 is a double pole switch 223 comprising spring contact members 223^a and 223^b normally biased out of contact but capable of being brought together by depression of a start and stop button 224. The latter switch controls directly the rotation of the mandrel and carriage feed and is connected in circuit with the clutch magnet 74.

Mounted in the rear wall of the motor box is a socket 225 adapted by means of a plug 226 to connect the phonograph to any suitable source of electric energy, such for instance as a 60-cycle house circuit. All of the electric devices included in the phonograph construction derive energy for operation from this source.

A manually operable switch 227 of any suitable construction is mounted beneath the base 50 of the machine, see Figs. 1 and 2. This switch, operable by means of a finger lever 228, serves as a main switch located between the plug and socket 225—226 and the various power receiving circuits of the machine. It will be understood that in accordance with known practice the switch 227 may be connected to a mouthpiece support or record-ejector for automatic operation thereby.

Circuit changer

Mention has been made of a circuit changing device 42. This is shown diagrammatically in

the wiring diagrams, Figs. 15, 16 and 17, as comprising in one operable unit a four-pole double throw switch having its central terminals *a* and *b* permanently connected by means of wires 230 and 231 to the input circuit of amplifier 40 and its central terminals *c* and *d* permanently connected by means of wires 232 and 233 to the output circuit of said amplifier, and a two-pole single throw switch having terminals *e* and *f* both permanently connected by wire 234 to a wire A', connecting the "cold" side of main switch 227 to contact 223^a of the start and stop switch 223. The "hot" side of switch 227 is connected by a main lead A with one contact of socket 225 and thus to one side of the power circuit. The other side of the power circuit is connected through socket 225 to a main return lead B.

The circuit changer 42 is normally biased by means of a spring 43 (see Fig. 1) in the position indicated in Fig. 16, at which time the machine is conditioned for recording but may be thrown to the backspace and reproducing position indicated in Figs. 15 and 17 by the energization of a magnet 44. Specific details of the structure of the circuit changer and its operative association with magnet 44 will be described more fully hereinafter.

The switch terminals *a*, *b*, *c* and *d* are respectively adapted to be connected alternatively with a set of terminals *a'*, *b'*, *c'*, *d'* or with a set of terminals *a''*, *b''*, *c''*, *d''* and the terminals *e* and *f* may be connected respectively with terminals *e''* and *f''*. The microphone 41 is connected by means of wires 235 and 236 with the terminals *a'* and *b'* and by means of wires 237 and 238 with switch terminals *c''* and *d''*. The recorder 78 is connected by means of wires 239 and 240 with terminals *c'* and *d'* and the reproducer 79 is connected by means of wires 241 and 242 with terminal *a''* and *b''*. Terminal *e''* is connected by a wire 243 with one end of the coil of clutch magnet 74 and also with contact 223^b of start and stop switch 223. Terminal *f''* is connected by a wire 244 with one end of the coil of the recorder and reproducer conditioning magnet 159. The other ends of the coils of magnets 74 and 159 connect with main return wire B.

A wire 245 connects line A' with contact 135^a of the backspace and circuit changer control switch 135. Contact 135^b is connected by wire 246 with contact 206 of the advance marker switch 204. Contact 135^c is connected by wire 247 with one end of the coil of the backspacer actuating magnet 132, the other end of which coil connects with return lead B. Contact 207 of advance marker switch 204 connects with wire 234 and thus with line A'. The wire 246 not only connects switch 204 with contact 135^b of switch 136 but also connects said contact with the circuit changer magnet 44 through wire 248, the magnet being also connected by wire 249 with return lead B. It will thus be seen that switches 204 and 135 are in shunt to one another in respect to magnet 44, each being therefore capable of controlling the operation of the circuit changer. The machine motor is connected between leads A' and B by means of wires 250 and 251 and the power supply for the amplifier 40 from leads A' and B is by means of wires 252 and 253.

Referring to Figs. 1, 13 and 14, the circuit changer 42 comprises an upright block 10, made of any suitable insulating material such as that known under the trade name of "Bakelite," which is secured to the bottom of the motor box by means of screws 11 threaded into an angularly

disposed portion 12 of the block. Through member 10 are threaded brass or other suitable metal screws 13 to provide the switch terminals a', b', c', d', and a'', b'', c'', d'', e'', f''. To the heads of these screws may be soldered the appropriate wires connecting them to their respective circuits. Secured within recesses 14 at the ends of the block 10 are a pair of bracket members 15, which carry at their extremities a pair of aligned screws 16 constituting pivots for supporting for oscillatory movement a second and smaller insulation block 17. U-shaped metallic plates 18 embracing the ends of block 17 are provided with sockets (not shown) adapted to cooperate with the pivot screws 16.

To the plate 18 at one end of the block 17 there is pivotally connected one end of a link 19, as by means of screw 20, the other end of which link is connected by means of a screw 21 to the armature 22 of the magnet 44. This magnet may be of any suitable construction and may be mounted as by means of a bracket 23 secured to the portion 12 of block 10. The armature 22 is mounted to rock about a pivot 24 toward the magnet pole 25, when the coil 26 is excited and thus effect a rocking movement of the block 17 against the reaction of the tension spring 43.

Rigidly mounted in the block 17 midway between the pairs of terminal screws 13 is a plurality of studs 27 each of which projects beyond the outer surface of the block 17 and has loosely mounted thereon a bridge member 28 made of brass or other conductive material. The ends of each of said bridge members are adapted to make contact with one or the other of the pairs of screws 13, as for instance with either a' or a'', depending upon whether the block 17 is under the control of the magnet or the spring. Of course where a bridge member is not intended to make double throw connections there will be no screw 13 placed to coat with one of its ends.

As was said above, each bridge member is loosely mounted on its respective stud but is normally held flatly against the surface of block 17 by means of a compression spring 29 which surrounds the stud and is held between washers 30. The outer washer is retained on the stud by a cotter pin 31. This mounting of the bridge members is provided so that they may make contact with one set of screws 13 before the block 17 has completed its rocking movement. Thus contact is assured without danger of doing damage to the bridge member or its supporting stud. To avoid damage by sparking when the switch contacts make and break, the coating surfaces are preferably coated with silver or some other suitable metal or metallic alloy.

Each bridge member is provided in the plane of the axis of the block 17 with a lug 32, overlying a hole 33 in the block 17, and directly behind the hole there is mounted in the block 10 a terminal screw 34 to which may be attached one of the permanent switch connections a, b, c, d, e or f. A short piece of flexible wire 35 connects each of these terminal screws with the lug of its respective bridge member. Since certain of the switch contacts are included in circuits carrying voice currents, the circuit changer is preferably shielded as by means of metal covers 36 and 37, and the contacts belonging to the several circuits which might have an inductive effect upon one another are preferably further shielded by means of metal partitions 38.

While the circuit changer has been described in detail it is not so claimed in the present ap-

lication since in its specific form it is not the joint invention of the present applicants.

Manner of operation

The operation of the dictating machine may be best understood by referring to the wiring diagrams, and first to Fig. 16, which shows the various circuits conditioned for recording. In this figure the main switch 227 is shown as having been closed to connect the power line A with the line A', and the switch 223 is also shown in closed condition by operation of the start and stop button 224 on the hand unit. The closing of these two switches closes the circuit through the clutch magnet 74 by way of leads A', switch 224, wire 243, and return lead B, and operates the clutch to start mandrel rotation since the circuit through the motor 58 has been completed with the closing of switch 227. Also the power supplied to the amplifier through wires 252 and 253 has become effective to supply energy to the tubes of the amplifier.

At this time the spring 43 holds circuit changer 42 in the condition indicated in Fig. 16. Thus the bridging members of the circuit changer have connected the switch contacts a, b, c and d with a', b', c' and d'. The microphone 41 is now operatively connected through wires 235, 236 to switch contacts a, b, and wires 230, 231, to the input of the amplifier, the output of the amplifier being connected by wires 232 and 233 to switch contacts c, d, and wires 239, 240 to the recorder 78.

Assuming that the carriage is in its initial position at the left end of the record cylinder and that the advance marker is in contact therewith, the contact members of switch 204 will be held out of engagement by the pin 201. The dictator may now make a record upon the record cylinder, continuing, should he desire, until the entire record is filled with recorded matter.

Should he at any time while dictating wish to repeat any portion of what he has said, he may do so by releasing the start and stop button 224 thus discontinuing the circuit through the switch 223, and by operation of the backspace button 136 cause engagement of the three contacts of switch 135 as indicated in Fig. 15. Under these conditions current will flow through lead A', wire 245 to switch contact 135^a, contact 135^b, wire 246, wire 248, circuit changer magnet 44 and wire 249 to wire B, thus energizing the magnet 44 and changing the circuit changer from its condition for recording to its condition for back-spacing and reproducing, the terminals a, b, c, d, e, f being connected with switch contacts a'', b'', c'', d'', e'', f''.

Through these new connections the reproducer 79 is connected to the input of the amplifier, the output of which is connected through the switch to the microphone 41 by wires 237, 238 connecting contacts c'', d'' with the wires 235, 236 of the microphone circuit. Simultaneously the recorder and reproducer control magnet 159 is energized through wires 234, contacts f, f', wire 244 and return lead B. With the energization of magnet 159 the lever 154 (see Figs. 3 and 7) is raised, lifting the recorder weight lever 146 and the stylus 143 so that the stylus is clear of the record, and by withdrawal from contact of the shoulder 175 with the arm 174 of lever 165, permitting lever 165 to swing forwardly under the reaction of spring 173 until the reproducing stylus 166 engages the sound record.

Simultaneously with the energization of the reproducer magnet, the clutch magnet 74 takes current from the circuit comprising wire 234, switch elements e , e'' and wire 243, and the backspace magnet 132 becomes energized by current flowing through wires A', wire 245, switch 135, wire 247, and return lead B. The energization of the backspace magnet causes the inter-

ponent member 119 to be thrown into the path of the cams 118 as above described thus effecting a repeated rocking of the rock shaft or carriage rod 80 in synchronism with the rotation of the belt pulley 57.

The rocking of the rock shaft effects step-by-step backspacing of the carriage for so long as the backspace switch 135 is held closed by means of the button 136. However, the first movement of the carriage in a backspacing direction separates the carriage from the advance marker and immediately the switch contacts 206, 207 engage one another closing a circuit through wires A', wire 234, switch 204, wire 248, circuit changer magnet 44, wire 249 and return wire B. Thus switch 204 has taken over the office of switch 136 in respect to the circuit changer magnet 44 causing the circuit changer to remain in the backspace reproducing position shown in Figs. 15 and 17 even after release of backspace button 136. This latter condition is shown in Fig. 17.

As a result, after the operator has backspaced as long as he wishes, he may release backspace button 136 on the hand unit, and, since the circuit changer is held in its reproducing position by means of the magnet 44, maintained as just described, the clutch magnet 74 will continue to be energized through switch contacts e , e'' , wire 243 and return lead B, and the operator may listen to the reproduction of the record from the point where backspacing stopped for as long as he chooses or until the carriage again comes in contact with the advance marker, when the carriage pin 201 again opens the contacts of switch 204, thus de-energizing the magnet 44, whereupon the circuit changer immediately goes back to recording condition, as in Fig. 16, under the influence of the spring 43, and all of the parts will again be completely conditioned for recording as soon as the operator presses the start and stop button 224 to close switch 223.

As related above, upon each operation of the rock shaft during backspacing, the reproducing stylus is moved to and held in a centralized position by reason of the engagement of notch 192 of lever 190 with the upper arm 162 of lever 161. Thus during backspacing the reproducing stylus is held against lateral movement and may glide backward over the record surface without being thrown out of position and thus be ready at the end of backspacing to take up its work of reproducing the recorded matter.

When the record has been made, or when the operator wishes to change cylinders, he may by raising the carriage lever 211 lock the advance marker to the side of the carriage and at the same time effect a rotation of lever 84 to disengage both the recording and reproducing stylus from contact with the record to effect a centralizing of the reproducing unit and raise the feed nut from the feed screw. He may then slide the carriage and advance marker by hand to their initial position. Upon release of carriage lever 211, lever 84 will remain in the raised position holding the stylus clear of the record

so that the record may be removed without danger of scratching its surface or damaging the recorder or reproducer mechanisms. After a new record has been put upon the cylinder the carriage lever 84 must be again lowered to bring the recording stylus down upon the record, preparing the machine for recording as above described.

It should be noted that in the event the carriage be conditioned neutrally by manipulation of lever 84 instead of lever 211 and then moved toward its initial position, the advance marker will not be locked in engagement with the carriage and so will be left in its position of farthest advance. Since this separation of carriage and marker slide will permit engagement of switch contacts 206 and 207, the magnet 44 will be energized to shift the circuit changer to reproducing position thus putting the clutch in driving condition if or when the feed wire A is connected to wire A' by means of the main switch 227. The machine will accordingly immediately become active to reproduce dictation after any such manually produced backward movement of the carriage.

We claim:

1. In a phonograph, a carriage supporting a recording stylus and a reproducing stylus alternatively shiftable into engagement with a record tablet, said carriage being mounted to advance or backspace in relation to said tablet, means for advancing said carriage, means for imparting a backspacing movement to said carriage, means for controlling the operation of said backspacing means, a relay operable in response to operation of said backspace controlling means, a shifting mechanism connected to and operable in response to operation of said relay to shift said reproducing stylus into engagement with said record table when said backspace control means is operated, and means associated with said carriage and connected to said relay independently of said backspace control means automatically to maintain said relay in operated position and said reproducing stylus in shifted position after backspacing movement has been imparted to said carriage.

2. In a phonograph, in combination, a carriage supporting a sound reproducing means operable in relation to a recording medium, said carriage being mounted to advance or backspace in relation to said medium, means for advancing said carriage including a clutch, means for imparting a backspacing movement to said carriage also including said clutch, means controlling the operation of said backspacing means, a relay operable in response to operation of said backspace controlling means, shifting means connected to and operable in response to operation of said relay to render both said reproducing means and said clutch operative when said backspace control means is operated, and means associated with said carriage and with a device for marking a point of farthest advance of said carriage connected to said relay independently of said backspace control means automatically to effect operation of said relay at any point in the path of travel of said carriage rearwardly of the point of travel of said carriage corresponding to the position occupied by said device.
